(57) **CLAIM**

The ornamental design for a bottle, as shown and described.

DESCRIPTION

FIG. 1 is an upper perspective view of a bottle showing my new design.

FIG. 2 is front view thereof;

FIG. 3 is a rear view thereof;

FIG. 4 is a side view thereof;

FIG. 5 is an opposite side view thereof;

FIG. 6 is a top plan view thereof;

FIG. 7 is a bottom plan view thereof; and,

FIG. 8 is a bottom perspective view thereof.

The oblique lines shown on the bottle represent transparency. The broken lines shown in FIGS. 1 and 6 represent the bounds of the claimed design.

1 Claim, 3 Drawing Sheets
